UNITED STATES PATENT OFFICE.

CHARLES W. MUELLER, OF ST. LOUIS, MISSOURI, ASSIGNOR TO LEWIS INVISIBLE STITCH MACHINE CO., OF ST. LOUIS, MISSOURI, A CORPORATION OF MAINE.

WORK-CRIMPING MECHANISM FOR BLINDSTITCH SEWING MACHINES.

Application filed February 14, 1924. Serial No. 692,695.

This invention relates to new and useful improvements in blind stitch sewing machines generally, although more particularly to improvements to the work crimping or bending mechanism such as, for instance, as is embodied in Patent No. 1,254,818, issued to John G. Lewis on January 29, 1918.

In said patent construction, when it is desired to stitch across pockets or other superimposed fabrics, the material will be pushed upwardly and crimped by the plunger, and, inasmuch as the needle travels in a constant path relative to the horizontal, said needle will penetrate not only the superimposed fabric or pocket but also the base fabric. Thus in the operation specifically noted, the line of stitching will close the pocket opening.

It is, therefore, one of the principal objects of this invention to provide means for limiting the upward crimping movement of the fabric, due to the movement of the plunger, and thereby maintain a predetermined depth of needle penetration in the material with relation to the upper face thereof, whereby in the operation above noted the stitching will be confined to the superimposed layer or pocket and consequently will not penetrate the base layer and close the pocket opening.

Another object of this invention is to provide a construction which will avoid the difficulties above enumerated, by providing readily accessible means for varying the depth of the needle penetration by limiting the upward movement of reciprocation of the plunger and operable subsequent to the initial adjustment of the plunger reciprocation relative to the path of the needle travel, thus providing a sewing machine capable of efficient use in many operations on garments, such as, the stitching of edge tape and bridles on coats, in which the depth of needle penetration must be adjusted to allow the needle to penetrate the edge tape or bridle and thence penetrate or partially penetrate the canvas lining, but not penetrate the base layer, that is, the material comprising the outside part of the coat.

Another object of the invention lies in the provision of a novel plunger adjusting mechanism which will reduce the wear thereof to a minimum, and consequently main-

tain an accurate relation between the plunger and the needle, and which will render the adjusting mechanism capable of ready assembly.

Other objects and features of the invention will more fully appear from the following description and claims in conjunction with the accompanying drawings, in which:

Figure 1 is a partial end elevation of a sewing machine embodying my invention.

Figure 2 is a horizontal sectional view taken on the line 2—2 of Figure 1.

Figure 3 is a vertical sectional view taken on the line 3—3 of Figure 2, the plunger being shown in its lowermost position.

Figure 4 is a similar view but showing the plunger in its highest position and the needle penetrating the material.

Figure 5 is an enlarged sectional view of the plunger mechanism.

Figure 6 is a perspective view of the presser-foot.

Figure 7 is a perspective view of the plunger adjusting mechanism, and

Figure 8 is a detail sectional view thereof.

Like reference numerals indicate corresponding parts in all the figures of the drawings.

My invention is directed generally to a vertically reciprocating plunger for crimping or bending the material in advance of each needle penetration, the plunger being yieldably supported relative to its actuating means and cooperating with an opening formed in a stationary presser-foot which is located on the upper side of the material. Means are provided for initially and bodily adjusting the position of the reciprocating movements of the plunger so that the high point of the plunger reciprocation may be initially located in a plane slightly below the path of the needle travel. In order to provide means for varying the depth of the needle penetration relative to the upper or stitching face of the material and without disturbing said initial adjustment of the plunger, I have provided a vertically adjustable stop cooperating with the upper face of the fabric and located directly above the upper end of the plunger. This stop is carried by a fixed part of the sewing machine, preferably the presser-foot, and af-

fords a readily accessible means for the operator when varying the depth of the needle penetration in the material, either during the running of the machine or while it is idle. As the stop is adjusted downwardly, the upward limit of movement of the plunger is correspondingly lessened and the material is correspondingly lowered. Inasmuch as the needle travel is in a fixed plane relative to the horizontal, it will follow that by adjusting the stop, the depth of the needle penetration in the material will be thereby varied. Should a pocket or other superimposed fabric pass under the stop, the yieldable plunger will give way, and consequently the depth of needle penetration relative to the upper face of the superimposed fabric will remain constant.

In the initial adjustment of the plunger mechanism it is necessary to maintain a uniform relation between the plunger and the needle and I have, therefore, provided a novel means for initially and bodily adjusting the reciprocatory movement of the plunger, whereby the wear, on the adjusting parts will be reduced to a minimum, and consequently the predetermined relation between the needle and the plunger will be maintained. This is very important, because any wear in the plunger adjusting mechanism will become manifest at the high point of the plunger reciprocation. This will result in the plunger moving upwardly into the path of the needle and thereby not only damaging or destroying the needle but causing resultant stoppage to the machine with the consequent loss of time in assembling new parts and readjusting the machine.

In carrying out my invention as shown by the accompanying drawings, the sewing machine includes the usual base 5 and overhanging head 6. The stitch forming mechanism is fully shown and described in Patent No. 1,176,415, issued to James Whitelaw, March 21, 1916, and the work presenting mechanism is fully described in the Lewis Patent No. 1,254,818, previously referred to, and it is thought that a general description thereof will be sufficient to enable any one skilled in this art to fully understand my invention.

The work presenting mechanism includes a presser-foot 7 detachably fixed to the head 6, a 4-motion feed dog 8 operating below the material and cooperating with the presser-foot 7 to intermittently feed the material through the machine, a vertically reciprocating plunger 9 for crimping or bending the material in advance of each needle penetration, and a vertically reciprocatory clamp 10 for clamping the material against the presser-foot during the needle penetration.

The presser-foot 7 is provided with an opening 11 directly above the plunger 9 for permitting the latter to project the material

through the opening in a crimped or bent formation and in a position to be penetrated by the needle 12. In this type of machine the needle 12 is oscillated about a fixed horizontal fulcrum 13 located on the stitching head 6. In this particular case the needle has a fixed path of travel relative to the horizontal and it also oscillates in a fixed vertical plane so as to always penetrate the crimped material at a point directly above the plunger. Cooperating with the needle 12 is any suitable complementary stitch forming mechanism and in this instance I have illustrated such as a rotary hook 14.

The 4-motion feed dog 8 is given its forward and backward movement by means of a rock-shaft 15, a rock arm 16 fixed to said shaft, and a link 17 pivotally connecting the feed dog and the rock arm. The up and down movement of the feed dog is created through a rock shaft 18 having a rock arm 19 fixed thereto, a bell-crank 20 fulcrumed on the frame at 21, a link 22 connecting the crank arm 19 to the vertical arm of the bell-crank, and a substantially vertically disposed link 23 pivotally connected at its lower end to the horizontal arm of the bell-crank 20 and at its upper end to the feed dog 8. The work clamp 10 is supported for vertical movements by a post 24 slidably mounted in the frame of the machine and is yieldably held in its extreme upper position by a flat spring 25 operating against the lower end of the post. The clamp substantially surrounds the feed dog and is pivotally supported on the post 24 by pivots 10^a. The plunger 9 is mounted to slide vertically within a barrel 26 which in turn is slidably mounted vertically in a guide opening 27 in the frame of the machine. A block 28 is slidably mounted in the frame and is provided with a lug 29 which extends laterally under the barrel 26. The lower end of the plunger 9 is provided with a reduced threaded end 30 which passes through a suitable opening formed in the lug 29, the reduced end forming a resultant shoulder 31. A coil spring 32 surrounds the reduced end 30 and lies between the lug 29 and the shoulder 31, the spring tending to urge the plunger 9 upwardly into the opening 11 of the presser foot. This upward movement of the plunger is limited by a nut 9^a fixed to the lower end of the plunger and cooperating with the lug 29. It will thus be seen that when the slide block 28 is moved up and down the plunger 9 will be correspondingly moved and whenever resistance is offered to the upper movement of the plunger the spring will permit the plunger to remain stationary while the barrel continues its upward movement. In order to reciprocate the plunger 9, a rock-shaft 33 is provided and this rock-shaft carries a rock-arm 34 having a link 35 pivoted as at 130

36. to its upper end, the other end of the link 35 being pivoted as at 37 to the slide block 28.

5. In the cyclic operation of the parts above described, as the needle is retracted from the material, the latter is moved by the feed dog a distance of one stitch length, the plunger and the clamp being at this time retracted to points below and out of engagement with 10. the material. The feed dog is then moved downwardly away from the material and returned to its starting position of feed movement. During this return movement of the feed dog the plunger is moved upwardly to engage and crimp the material in the opening of the presser-foot, and the clamp is also moved upwardly to clamp the material against the foot and on opposite sides of the plunger, the clamping action serving to hold 15. the crimped material against lateral movement or "creeping" during the following needle penetration of said crimped material. While the material is thus being held in its crimped position, the needle penetrates the 20. same and the rotary hook cooperates with the needle thread to form a resultant stitch. The needle is then retracted and the plunger and clamp lowered, thus completing the 25. cycle of operation.

30. As above pointed out, it is necessary to provide means for initially adjusting the vertical position of reciprocation of the plunger relative to the path of needle travel and I have, therefore, provided in the train of actuating mechanism for the plunger, an adjustable means whereby the bodily movement of reciprocation of the plunger may be vertically adjusted initially relative to the path of needle travel. To this end the rock arm 34 is formed with an elongated opening 38 and with a laterally extending bearing arm 39. Fixed to the rock-shaft 33 by a set screw 40 is a holder 41 having a radially extending threaded bore 42. The bearing 45. arm 39 of the rock arm 34 is formed with a ball socket 43 which is disposed in alignment with the threaded bore 42. An adjusting screw 44 has threaded engagement with the bore 42, and this screw has a reduced outer end 45 forming a resultant shoulder 46, the outer end 45 passing through the ball socket 43. The reduced end 45 of the screw is threaded for engagement with a ball 47 which is adapted in turn to be seated in the 50. ball socket 43. A clamping nut 48 is threaded onto the outer end of the reduced end 45 of the screw and serves to lock the ball 47 against movement relative to said adjusting screw. In order to provide means for easily 55. handling and thereby adjusting the screw, I have formed the ball 47 with an integral circular head 49 and have formed the periphery thereof with a series of notches 50. A spring 51 which in this instance is shown 60. as a dished flat metal spring is disposed be-

tween the adjusting screw 44 and the crank arm 34, this spring being centrally formed with an opening to receive the reduced end 45 of the screw. Thus, the spring has its central portion disposed against the shoulder 70. 46 of the screw and its peripheral portion against the bearing arm 39 of the rock arm. The function of this spring is to yieldingly maintain the ball in contact with its socket, and thereby automatically take care of any 75. variations between the parts due to wear thereof. By providing a ball and socket connection, I have provided a construction which will readily permit the assembling of the parts, although slight inaccuracies of 80. manufacture should occur in the alignment of the bore 42 with the socket 39. In order to automatically latch the adjusting screw in any position of adjustment, I have provided a spring latch 52 and have secured the 85. same to the rock-arm 34 by means of a screw, said latch extending downwardly below the bearing arm 39 and having its free end engageable with any of the notches 50 formed in the circular head 49 of the ball 47. 90.

When initially setting up or adjusting the machine, it is desirable to have the position of reciprocation of the plunger in such a location as to insure the high point of reciprocation being disposed slightly below the path 95. of needle travel. This adjustment may be readily obtained by the above described mechanism as it will be apparent that by adjusting the screw 44 the rock-arm 34 will be moved across the axis of the rock-shaft 33 and the vertical position of the slide 28 which carries the plunger will be correspondingly adjusted. It will also be noted that when this adjustment has been completed the parts 100. will be held against accidental displacement by means of the spring latch 52, and that any wear on the parts comprising the adjusting mechanism will be automatically taken up by the flat spring 51, thus avoiding any 105. loose connections and the resultant overthrow of the plunger relative to the path of needle reciprocation. 110.

From the foregoing, it will be noted that when the plunger mechanism is adjusted so that the high point of reciprocation is located directly below the path of needle travel the maximum needle penetration in the material will be assured. It is desirable to vary the depth of the needle penetration in the material relative to the upper 115. face thereof in order to meet the various practical requirements of garment manufacture. It is desirable to provide a readily accessible means for accomplishing this purpose either during the running of the machine or while it is idle, and to this end I have provided a vertically adjustable stop which is disposed above the path of plunger reciprocation and bears against the upper 120. face of the fabric so as to variably limit the 125. 130.

upward movement of the plunger. This adjustable stop is carried by a fixed part of the sewing head and in this particular instance, I have positioned the stop on the 5 presser-foot 7. This stop consists of a lever 54 fulcrumed intermediate its ends on a horizontal pivot pin 55 which is carried by upstanding ears 56—56 formed on the presser-foot. The lever 54 comprises an adjusting arm 57 and a work engaging arm or stop 58. The lever is disposed entirely on one side of the path of needle reciprocation and the axis of the fulcrum 55 is disposed parallel to the needle reciprocation. 10 The lever is so positioned on the presser-foot that the work engaging arm or stop 58 extends downwardly and registers with the opening 11 of the presser-foot and is disposed directly above the path of reciprocation of the plunger. An adjusting screw 59 is threaded into the outer end of the adjusting arm 57 and bears against the presser-foot 7. The upper end of this adjusting screw 59 is provided with a head 60 having its periphery formed with a plurality of notches 61 for automatic engagement by a spring latch 62 fixed to the presser foot by a screw 63. By turning the screw 59 in a clock-wise direction the adjusting arm 57 of the lever will be moved upwardly about its fulcrum 55 and consequently the work engaging arm or stop 58 will be lowered relative to the path of needle reciprocation, thus lowering the high point of reciprocation of the plunger and thereby lessening the depth of needle penetration in the material. This stop will be automatically held in any position of adjustment by the spring latch 62 cooperating with the notches 61 of the adjusting screw 59. When it is desired to increase the depth of needle penetration in the material, the adjusting screw 59 is, of course, turned in an anti-clock-wise direction, and the reverse movement of the lever 57 will be brought about. 20

From the foregoing it will be observed that I have provided means for bodily adjusting the position of reciprocation of the plunger preparatory to varying the high point of movement of the plunger in order to predetermine the depth of needle penetration in the material.

I claim:—

1. In a blind stitch sewing machine, the combination with a stitch forming mechanism including a reciprocatory needle operating in a constant path, of a work presenting mechanism operating below the stitch forming mechanism, a presser foot disposed above the work, a vertically reciprocatory means operating below the work material for upwardly bending the latter in advance of and for each needle penetration, and a stop adjustable vertically relatively to said presser foot and located directly above said

bending means and above said material for positively limiting the upward movement of said material bending means to thereby limit the depth of the needle penetration in the material. 70

2. In a blind stitch sewing machine, the combination with a work presenting mechanism, of a stitch forming mechanism including a reciprocatory needle operating in a constant path from a point above the work presenting mechanism, means for upwardly bending the work material in advance of the needle penetration including an intermittently actuated vertically movable plunger operating from below the material, and a vertically adjustable stop disposed above the material and directly above the plunger for predetermining the upward limit of movement of the plunger to thereby limit the depth of the needle penetration in 85 the material, relative to the upper face thereof.

3. In a blind stitch sewing machine, the combination with a work presenting mechanism, of a stitch forming mechanism including a reciprocatory needle operating in a constant path from a point above the work presenting mechanism, means for upwardly bending the work material in advance of the needle penetration including an intermittently actuated vertically movable plunger operating from below the material, a stop lever fulcrumed above the material for positively limiting the upward movement of the plunger to thereby limit the depth of the needle penetration in the material, relative to the upper face thereof, and means for adjusting the lever on its pivot to vary the upward limit of movement of the plunger to thereby vary the depth of the needle penetration in the material relative to the upper face thereof. 95

4. In a blind stitch sewing machine, the combination with a work presenting mechanism including a presser foot having a material-receiving opening, of a stitch forming mechanism including a reciprocatory needle operating in a constant path across the opening in the foot from a point above the latter, means for bending the material into the opening of the foot in advance of each needle penetration including an intermittently actuated vertically movable plunger operating from below the material, and means above the material for positively limiting the upward movement of the plunger to thereby limit the depth of the needle penetration relative to the upper face of the material. 110

5. In a blind stitch sewing machine, the combination with a work presenting mechanism including a presser-foot having a material receiving opening, of a stitch forming mechanism including a reciprocatory needle operating in a constant path across 125

the opening in the foot from a point above the latter presser-foot, means for bending the material into the opening of the foot in advance of each needle penetration including an intermittently actuated vertically movable plunger operating from below the material, and means above the material and separate from the plunger for positively limiting the upward movement of the plunger to thereby limit the depth of the needle penetration relative to the upper face of the material.

6. In a blind stitch sewing machine, the combination with a work presenting mechanism including a presser-foot having a material-receiving opening, of a stitch forming mechanism including a reciprocatory needle operating in a constant path across the opening in the foot from a point above the latter, means for bending the material into the opening of the foot in advance of the needle penetration including an intermittently actuated vertically movable plunger operating from below the material, and means including a lever and an adjustable stop therefor located above the material and separate from the plunger for positively limiting the upward movement of the plunger to thereby limit the depth of the needle penetration relative to the upper face of the material.

7. In a blind stitch sewing machine, the combination of a presser-foot having a cloth opening, a plunger to work into said cloth opening, means for reciprocating said plunger towards and away from said opening and having a yieldable connection with said plunger, and a relatively vertically adjustable stop located above the material to limit the high point of reciprocation of said plunger.

8. In a blind stitch sewing machine, the combination of a presser-foot having a cloth opening, a plunger to work into said cloth opening, means for reciprocating said plunger towards and away from said opening and having a yieldable connection with said plunger, and a relatively vertically adjustable stop mounted on the presser foot to limit the high point of reciprocation of said plunger.

9. In a blind stitch sewing machine, the combination of a presser-foot having a cloth opening, a plunger to work into said cloth opening, means for reciprocating said plunger towards and away from said opening and having a yieldable connection with said plunger, a stop lever fulcrumed on the presser foot to limit the high point of reciprocation of said plunger, and means for adjusting said lever to vary the high point of reciprocation of the plunger.

10. In a blind stitch sewing machine, the combination of a presser foot having a cloth opening, a plunger to work into said cloth

opening, means for reciprocating said plunger towards and away from said opening and having a yieldable connection with said plunger, a stop lever fulcrumed on the presser foot to limit the high point of reciprocation of said plunger, means for adjusting said lever to vary the high point of reciprocation of the plunger, and means for automatically latching said adjusting means in any position of adjustment.

11. In a blind stitch sewing machine, the combination of a presser foot having a cloth opening, a plunger to work into said cloth opening, means for reciprocating said plunger towards and away from said opening and having a yieldable connection with said plunger, a stop lever fulcrumed on the presser foot to limit the high point of reciprocation of said plunger, means for adjusting said lever to vary the high point of reciprocation of the plunger, said adjusting means comprising a screw threaded into the end of the lever opposite the material-engaging end thereof and bearing against the presser foot.

12. In a blind stitch sewing machine, the combination with a stitch forming mechanism including a reciprocatory needle operating in a constant path relative to the horizontal, of a work presenting mechanism operating below said stitch forming mechanism, a vertically reciprocatory plunger operating below the work material for upwardly bending said material in advance of each needle penetration, actuating means for said plunger including a yieldable connection, and vertically adjustable stop located above the material and directly above the plunger for variably limiting the extreme upward movement of the plunger to thereby vary the depth of the needle penetration in the material.

13. The combination of a presser foot formed with an opening for receiving upwardly crimped material, and a stop carried by the foot and vertically adjustable relatively thereto for limiting the upward movement of the material within said opening, said stop being disposed above the opening of the foot.

14. The combination of a presser foot formed with an opening for receiving upwardly crimped material, and a vertically adjustable stop carried by the foot for limiting the upward movement of the material within said opening, said stop including a lever having one end disposed above the opening of the foot.

15. The combination of a presser foot formed with an opening for receiving upwardly crimped material, a lever having one end disposed above the opening of the foot for limiting the upward movement of the material within said opening, and means for adjusting said lever to a predetermined posi-

tion to vary the vertical position of the material-engaging end of said lever.

16. The combination of a presser foot formed with an opening for receiving upwardly crimped material, a lever having one end disposed above the opening of the foot for limiting the upward movement of the material within said opening, means for adjusting said lever to a predetermined position to vary the vertical position of the material-engaging end of said lever, and means for automatically latching said adjusting means in any position of adjustment.

17. The combination of a presser foot formed with an opening for receiving upwardly crimped material, a lever having one end disposed above the opening of the foot for limiting the upward movement of the material within said opening, and means for adjusting said lever to a predetermined position to vary the vertical position of the material-engaging end of said lever, said adjusting means comprising a screw threaded into the end of the lever opposite the material-engaging end thereof and bearing against the presser foot.

18. The combination of a presser foot formed with an opening for receiving upwardly crimped material, a lever having one end disposed above the opening of the foot for limiting the upward movement of the material within said opening, means for adjusting said lever to a predetermined position to vary the vertical position of the material-engaging end of said lever, said adjusting means comprising a screw threaded into the end of the lever opposite the material-engaging end thereof and bearing against the presser foot, and a spring latch carried by the lever for engaging the screw to retain the latter in an adjusted position.

19. In a blind stitch sewing machine, the combination with a stitch forming mechanism including a reciprocatory needle operating in a constant path relative to the horizontal, a work presenting mechanism operating below said stitch forming mechanism, a vertically reciprocatory plunger operating below the work material for upwardly bending said material in advance of each needle penetration, actuating means for said plunger including a yieldable connection, and a vertically adjustable stop located above the material and directly above the plunger for variably limiting the extreme upward movement of the plunger to thereby vary the depth of the needle penetration in the material, said plunger actuating means including means for bodily varying the position of reciprocation of the plunger relative to the path of the needle travel.

20. In a blind stitch sewing machine, the combination with a stitch forming mechanism including a reciprocatory needle operating in a constant path, a work presenting

mechanism operating below said stitch forming mechanism, a vertically reciprocatory means operating below the work material for upwardly bending the latter in advance of and for each needle penetration, and means including a vertically adjustable stop located above said material and directly above said bending means and at one side of the path of needle travel for positively limiting the upward movement of said material bending means to thereby limit the depth of the needle penetration in the material.

21. In a blind stitch sewing machine, the combination of a reciprocatory plunger, and means for actuating said plunger including means for bodily adjusting the position of reciprocation of the plunger, said actuating and adjusting means comprising a rock-shaft, a rock-arm adjustable lengthwise across the axis of said shaft and provided with a ball socket having its axis parallel to said arm, a link connecting said plunger and said arm, and means for adjusting said rock-arm comprising a radially extending adjusting screw engageable and rockable with said shaft, a ball fixed on said screw and engageable in the socket of said rock-arm, and a spring carried by the rock-arm for maintaining said ball and socket in contact.

22. In a blind stitch sewing machine, the combination of a reciprocatory plunger, and means for actuating said plunger including means for bodily adjusting the position of reciprocation of the plunger, said actuating and adjusting means comprising a rock-shaft, a rock-arm adjustable lengthwise across the axis of said shaft and provided with a ball socket having its axis parallel to said arm, a link connecting said plunger and said arm, and means for adjusting said rock-arm comprising a holder fixed to said rock-shaft and formed with a radially extending threaded bore, an adjusting screw having threaded engagement with the bore of said holder, a ball fixed on said screw and engageable in the socket of said rock-arm, and a spring carried by the rock-arm for maintaining said ball and socket in contact.

23. In a blind stitch sewing machine, the combination of a reciprocatory plunger, and means for actuating said plunger including means for bodily adjusting the position of reciprocation of the plunger, said actuating and adjusting means comprising a rock-shaft, a rock-arm adjustable lengthwise across the axis of said shaft and provided with a ball socket having its axis parallel to said arm, a link connecting said plunger and said arm, and means for adjusting said rock-arm comprising a radially extending adjusting screw engageable and rockable with said shaft, and formed with a reduced outer end forming a resultant shoulder, a

ball fixed to the reduced outer end of said screw and engageable in the ball socket of said rock-arm, and a spring interposed between the shoulder of the screw and the 5 rock-arm for maintaining said ball and socket in contact.

24. In a blind stitch sewing machine, the combination of a reciprocatory plunger, and means for actuating said plunger including 10 means for bodily adjusting the position of reciprocation of the plunger, said actuating and adjusting means comprising a rock-shaft, a rock-arm adjustable lengthwise across the axis of said shaft and provided 15 with a laterally extending bearing arm having a ball-socket formed therein, the axis of the socket being parallel to the rock-arm, a link connecting said plunger and said arm, and means for adjusting said rock-arm comprising a radially extending adjusting screw engageable and rockable with said shaft, a ball fixed on said screw and engageable in the socket of said rock-arm, and a spring carried by the rock-arm for maintaining said 20 ball and socket in contact.

25. In a blind stitch sewing machine, the combination of a reciprocatory plunger, and means for actuating said plunger including means for bodily adjusting the position of reciprocation of the plunger, said actuating and adjusting means comprising a rock-shaft, a rock-arm adjustable lengthwise across the axis of said shaft and provided with a ball socket having its axis parallel to 30 said arm, a link connecting said plunger and said arm, and means for adjusting said rock-arm comprising a radially extending adjusting screw engageable and rockable with said shaft, a ball fixed on said screw and engageable in the socket of said rock-arm, a spring carried by the rock-arm for maintaining said ball and socket in contact, and means for latching the screw in any position of adjustment. 35

26. In a blind stitch sewing machine, the combination of a reciprocatory plunger, and means for actuating said plunger including means for bodily adjusting the position of reciprocation of the plunger, said actuating and adjusting means comprising a rock-shaft, a rock-arm adjustable lengthwise 40

across the axis of said shaft and provided with a ball socket having its axis parallel to said arm, a link connecting said plunger and said arm, and means for adjusting said 55 rock-arm comprising a radially extending adjusting screw engageable and rockable with said shaft, a ball fixed on said screw and engageable in the socket of said rock-arm, a spring carried by the rock-arm for 60 maintaining said ball and socket in contact, and a spring latch carried by the rock-arm and co-operating with the screw to retain the latter in any position of adjustment.

27. In a blind stitch sewing machine, the combination with a stitch forming mechanism including a reciprocatory needle operating in a constant path, a work presenting mechanism operating below said stitch forming mechanism, a vertically reciprocatory 70 means operating below the work material for upwardly bending the latter in advance of and for each needle penetration, a stop located above said material and directly above said bending means, and means for 75 vertically adjusting said stop during the running of the machine for positively limiting the upward movement of said material bending means to thereby limit the depth of the needle penetration in the material. 80

28. In a blind stitch sewing machine, the combination with a stitch forming mechanism including a reciprocatory needle operating in a constant path, a work presenting mechanism operating below said stitch forming mechanism, a vertically reciprocatory means operating below the work material for upwardly bending the latter in advance of and for each needle penetration, a stop located above said material at one 85 side of the path of the needle reciprocation and directly above said bending means, and means for vertically adjusting said stop during the running of the machine for positively limiting the upward movement of said material bending means to thereby limit the depth of the needle penetration in the material. 90

In testimony whereof I hereunto affix my signature.

CHARLES W. MUELLER.
